GOVERNOR

Albert Kalin, Cleveland, Ohio

Application May 1, 1943, Serial No. 485,313

10 Claims. (Cl. 264—3)

1

This invention relates to an improvement in governors of the type adapted to control the speed of prime movers (e. g. Diesel engines) when subject to varying load, and more particularly to an improvement in such governors which provides for more accurate speed control by the governor upon starting the prime mover from rest and the prevention of over-shooting in speed and excessive hunting during acceleration from standstill to an adjusted speed. This application is a continuation in part of my copending application Serial No. 385,228, filed March 26, 1941 (now Patent No. 2,324,514).

Under certain conditions serious damage can be done to prime movers by attempting repeatedly to increase power input thereto at too high a rate. Diesel engines if operated at nearly maximum capacity can be damaged by injecting too much fuel during acceleration under load and when cold. Also too rapid a rate of acceleration causes the speed of the prime mover to rise above the adjusted speed of the governor with consequent prolonged hunting. The present invention is concerned mainly with an arrangement for preventing operation of a speed regulating servo-motor of the governor in power-input-increasing direction from a condition of standstill at rates which might cause damage to the engine or cause pronounced hunting at starting as a result of the engine greatly overshooting the adjusted speed as the governor assumes control, while nevertheless enabling acceleration of such engine from zero fuel to idling fuel at a rate insuring positive governing and deceleration at such a rate as to prevent the engine from stalling when the speed level setting is suddenly reduced to a low level. The foregoing indicates one object hereof, and the term "cushioned start" as hereinafter used refers to the function of the present governor mechanism in so controlling the rate of acceleration from standstill that excessive hunting is greatly reduced or prevented.

Other objects are to provide means, effective only upon starting of a prime mover, for (1) preventing radical overshooting of speed and (2) delaying the speed adjusting operation of the governor in respect to the prime mover.

Another object is to provide a hydraulic damping means, effective only upon starting of a governed prime mover, for controlling the speed adjusting operation of the governor so as to prevent the prime mover from greatly overshooting the set speed.

Still another object is to provide in a hydraulic relay governor for a prime mover an auxiliary

2

servo-motor which, during starting of the prime mover, temporarily reduces the effective force of a speeder spring such as usually interposed between the manual or power driven speed adjusting means and a hydraulic pilot valve for controlling the speed regulating operation of a main servo-motor.

A further object is to provide in a governor for a prime mover a hydraulically acting means operating automatically at commencement of governor operation to delay the full application of the effective force of manual speed setting means on the automatic speed governing means.

A still further object is to combine the cushioned start operation with that of a hydraulically operable speeder-spring-adjusting power head.

The drawing shows one illustrative form of governor mechanism on which the invention can be used which is essentially the one shown in my Patent No. 2,219,229, issued October 22, 1940.

Fig. 1 is a central vertical sectional assembly view of a governor incorporating the present invention; Fig. 2 is a sectional view taken generally at 2—2 of Fig. 1; and Fig. 3 is a fragmentary detail sectional view of a modification which may be used to render unnecessary an auxiliary "cushioned start" servo-motor such as shown in Fig. 1.

The principal parts and assemblies of the illustrative governor mechanism are indicated mainly by letters and the special subject matter hereof usually by numerals.

In Fig. 1, a base casting W defines a lower portion of a sump S which lower portion is in open communication through a duct (not shown) with an upper portion of the sump S in a power case X. A gear pump partly shown at X' coupled with a main drive shaft W' is arranged to cooperate with a well known reversible check valve system (only partly shown) and appropriate fluid ducts to enable the pump to draw fluid from the lower part of the sump S and deliver it to a suitable accumulator, such as shown in said copending application, which accumulator functions to maintain a more constant hydraulic pressure than could be maintained by the pump alone in view of changes in speed that would be imparted to the pump as the load is changed on the governed engine.

Fluid from the accumulator is supplied as through passages X" to a governor port E and continuously therebeyond through a duct E' to an upper face F of a double acting hydraulic speed regulating servo-motor power piston G. The port E is controlled by a lower land portion of a pilot valve plunger H rotatable and slidab

axially in a pilot valve sleeve H' and which plunger, if moved downwardly from the normal position in which it is shown, opens the port E to a duct I and thereby to the lower and effectively larger face J of the power piston G, causing upward movement of said power piston. Upward movement of the pilot valve plunger H from its normal position causes an upper land portion thereof to vent the duct I at a port K, dumping pressure fluid from below the power piston G into the upper portion of the sump S and causing the piston G to descend by reason of the constant pressure maintained at the piston face F through the duct E'.

The pilot plunger H is moved axially in opposite directions as a result of the difference between centrifugal force on a set of fly balls L suitably rotated by the prime mover and an opposing force exerted by an adjustable speeder spring M, so that an increase in speed on part of the prime mover raises the pilot valve plunger H and a decrease in speed lowers said plunger. Regulation of speed by the servo-motor power piston G incident to change in load is initiated by such movement of the pilot valve plunger H. An automatic adjusting connection between the speeder spring M and the pilot valve plunger H which serves to provide a cushioned start of the prime mover will be described subsequently.

Power input to the governed prime mover is increased by raising the power piston G and decreased by lowering said piston as indicated on the drawing. Thus, in governing, for example, a Diesel engine, an increase in load causes decreased centrifugal force on the fly balls and lowering of the pilot valve plunger, thus initiating an increase in the rate of supply of fuel to the engine; and a decrease in load causes raising of the pilot valve plunger and consequent decrease in the rate of supply of fuel.

A hydraulic relay governor arrangement such as thus far described requires stabilization in order to prevent sustained vacillation in speed or hunting consequent upon load change and subsequent speed-correcting operation of the governor. The stabilizing mechanism includes a hydraulic compensation system supplied with fluid from the sump and actuating and receiving compensation pistons of said system operating as a function of regulating movement of the servo-motor piston G to damp or check each movement of said piston and prevent temporary overregulation of the prime mover thereby.

The actuating compensation piston N works in a trunk portion of the power piston G and displaces hydraulic fluid in a duct O leading to a receiving compensating piston P, slidably and rotatably mounted in the lower portion of the pilot valve sleeve H', whenever the power piston G starts to perform a speed regulating operation in either direction. The motion of the receiving compensation piston P is always opposite the regulation-initiating movement of the pilot valve plunger H, and places temporary primary yielding compensating restraint on such movement of the plunger H through the intermediary of a coil spring Q connecting the compensating piston P and the valve plunger H. The primary compensating force is removed, after regulation is effected, by relieving the positive or negative pressure in the duct O through an adjustable secondary compensation leak-off needle valve R communicating the duct O with the sump S through the upper part of the actuating compensating piston N.

As fully explained in said copending application, the fly balls L cause continuous rotation of the pilot valve plunger H in its coacting fixed valve sleeve H' through friction or other driving contact of the ball arm fingers with a disc portion h of the pilot valve plunger; and the spring Q is so connected with the plunger H and receiving compensating piston P that the piston is likewise rotated in the valve sleeve H'. This eliminates the possibility of binding of either the valve plunger H or the piston P due to foreign matter in the hydraulic fluid and assures that the pilot valve is free from static friction and therefore free to respond to very slight changes in speed. The spring Q also allows relative axial movement between the parts connected thereby so that the valve is always free to respond promptly to any change in centrifugal force acting on the fly balls L.

In operation, when the engine load is increased the resultant decrease in speed causes relative inward movement of the fly balls; lowering of the pilot valve plunger H; opening of the port E; admission of hydraulic fluid through duct I to the lower side of the power piston G; and increase of fuel to the engine. The upward movement of the piston G pumps fluid through duct O; raising the receiving compensating piston P, compressing the spring Q and exerting a slight upward force on the pilot valve plunger H sufficient to offset the temporary overbalance of speeder spring force relative to the centrifugal force on the fly balls, thus closing the port E. The port E is ordinarily closed quickly enough to prevent overtravel of the power piston G in the speed correcting direction; and, as the engine returns to normal speed, the compression force of the spring Q is dissipated by reason of leakage of fluid from the duct O into the sump S through the secondary compensation leak-off aperture of the needle valve R.

The mechanism operates the same as described above for a decrease in load except that all the movements are reversed, the compensating spring Q being placed in tension by suction action of the compensation fluid system, and hydraulic fluid being finally drawn from the sump into the duct O through the aperture of the needle valve R to relieve said tension.

For adjusting the speed of the engine to a predetermined value at which it continues to operate steadily after starting and after any load change with an ensuing brief period of speed stabilization effected by the governor, a suitable speed setting mechanism such as shown at the upper part of Fig. 1 may be used, said mechanism being essentially that shown in my said Patent No. 2,324,514. As illustrated, a speeder lever U which cooperates with the pilot valve plunger H through the intermediary of the speeder spring M has intermediately of its ends a pivotal connection (trunnion pin connection, not shown) with a speeder plug V against which the upper end of the speeder spring M is operatively maintained or to which the spring may be secured as at spring-coil-receiving thread-like grooves on the lower end of a screw Y threaded into the speeder plug V and locked in position as by a lock nut Y'. The lower end of the speeder spring M is operatively associated with the pilot valve plunger H in a manner to be described later.

One end of the speeder lever U (right as shown) has a pivotal support Z which, for the present purposes, may be considered fixed so that downward movement of the left or opposite end of

the lever U compresses the speeder spring M and sets the governor for higher than assumed speed and upward movement of said left end relieves the speeder spring M and sets the governor for lower than assumed speed.

Speed setting could, obviously, be accomplished by any mechanism connected to the left end of the speeder lever U and operable to raise and lower that end of the lever, but in the present instance the mechanism includes a hydraulically operated valve-adjusted power head 10 and means (e. g. manual or motor driven) to adjust the valve of the power head.

As shown in Fig. 1, the left end of the speeder lever U is pivoted to an upright stem 11 of a power head piston 12 which operates in a vertical cylinder bore 14 formed in a power head case 15 (part of the usual speeder case) a portion of which power head case extends below the top of the power case X as shown. The stem 11 is slidably guided for vertical movement in a cap 16 closing the upper end of the power head cylinder bore 14. The left end of the speeder lever U is bifurcated to straddle the stem 11 and is provided with axially aligned horizontal pins 18, the proximate ends of which pivot in a ring 19 (cf. Fig. 3) clamped against an annular shoulder formed at the upper end of the power head piston stem 11 as by a nut 20 and lock nut 20' threaded on the end of the stem 11.

The power head piston 12 is actuated hydraulically and is controlled by a follow-up valve 21, the stem 21' of which is slidably within an axial bore 17 of the piston stem 11, so that the piston moves up and down with the valve, i. e. as the valve stem 21' is moved up and down. The valve 21 admits fluid from an outlet duct of the accumulator, as later described, into operative relation to the piston 12 for movement of the latter up and down exactly as the valve 21 is moved. The valve requires very little power to operate it, and thus the power required for changing speed, manually or by (e. g.) a Selsyn motor, may be made independent of the variable resistance of the speeder spring M in opposing speed adjustment. The available hydraulic power from the constant pressure source is always more than adequate to overcome the force of the speeder spring at any degree of compression thereof. Thus the power head is useful: (a) in preventing lag on the part of (e. g.) a Selsyn motor due to resistance by the speeder spring M, and (b) in preventing the speeder spring M from disturbing the manually adjusted speed setting.

Constant pressure is applied to the upper side of the power head piston 12, to move the piston downwardly, through a duct comprising a vertical bore 22 in the power case X communicating with a bore 23 thereof leading from the accumulator discharge system and bores in the power head case 15 comprising, as shown, a diagonal bore 24 and a horizontal bore 25. The same pressure is applied to the lower and larger face of the piston 12 to move the piston upwardly as will be described presently.

The power head valve 21 has a cylindrical plug 28 on the lower end of the valve stem 21', which latter does not seal the bore 17 of the piston stem 11 above the plug, whereas the plug 28 is in sealing relation to the portion of the bore 17 in which it slides. As shown more clearly in Fig. 2, the valve stem 21' is non-circular in cross-section and thus free passages for fluid are pro-

vided between its perimeter and the walls of the bore 17.

The plug 28 normally blocks two lateral ports 29 and 30 in the stem 11 of the power head piston 12. The port 29 communicates freely with the power head cylinder below the piston 12 through a duct 31; and the port 30 communicates directly with the effectively smaller cylinder above the piston 12. When the plug 28 is moved downwardly by the speed setting mechanism, fluid from the cylinder 14 below the piston 12 is vented to sump or atmosphere from a land portion 32 along the valve stem 21', i. e. between its non-circular perimeter to the cylindrical bore 17 in the piston stem 11, whereupon pressure applied on the upper face (smaller effective area) of the piston 12 moves the piston downwardly until the plug 28 again blocks the port 29. Similarly when the plug 28 is raised it unblocks the port 30 admitting constant pressure to the lower end of the power head cylinder 12, thus raising the piston to whatever extent the plug 28 has been raised and then blocking the port 30, stopping further upward travel of the piston.

While hydraulic fluid is being admitted to the lower side of the power head piston 12 there is a tendency for fluid, so admitted, to raise the valve plug 28 against the restraining influence of the speed setting mechanism thereon through the stem 21'. The force thus temporarily exerted on the relatively small plug during speed adjustment is too small to be of any consequence, and as soon as the power head piston rises and closes the port 30 the tendency to force the plug 28 upwardly ceases.

For operating the power head valve 21, the upper end of the valve stem 21' has a trunnion block 34 fastened thereto as by a nut 35 threaded on the upper end of the stem 21' and forcing the block 34 against an annular shoulder on the stem. A bell crank 36 suitably pivoted at 38 has a forked arm 39 with tines slidably embracing trunnion pins 40 of the block 34 (cf. Fig. 3) and has an upstanding arm 41 arranged to be operated upon by a rock shaft 42 through a compressible but non-extensible link connection generally designated 44. The rock shaft 42 may be turned by a manually settable lever (not shown) directly or through the intermediary of a suitable speed adjusting motor drive, such as a Selsyn system, as is well known in the art.

For preventing radical overshooting of speed beyond the desired normal running speed at the start of operation of the engine, i. e. to provide for a "cushion start," there is included a servomotor 50 between the upper end of the pilot valve plunger H and the speeder spring M. This servo-motor can be supplied with hydraulic fluid partly through an axial bore of the pilot valve plunger which supplies oil for lubrication of the ball-head bearing. This is the principal reason for locating the "cushion start" servo-motor at the top of the pilot valve plunger. Otherwise it could just as well be above the speeder spring. It can, incidentally, be used as an interponent between any of the connected parts of speed adjustment mechanism, as between the power head piston 12 and speeder lever U.

As shown in Fig. 1, a servo-motor cylinder 51 is made rigid with the pilot valve plunger H of the ball arm finger thrust member h thereof, and a lower speeder spring retainer or perch 52 includes a piston 54 fitted to the cylinder 51. The pilot valve plunger H is centrally bored at 55 from its lower end (lower end of bore suitably

7
 plugged), and the bore extends upwardly past a groove 56 (normally at the port E) of the lower portion of the plunger H and communicates with the groove by reason of cross holes 58. The groove 56 being opposite the constant pressure port E of the pilot valve sleeve, during normal running speed of the engine, is normally continuously supplied with hydraulic fluid under substantial pressure. Part of the fluid so supplied to the axial bore 55 is taken from said bore 10 at an upper groove 60 through radial holes in the plunger communicating with the bore and the latter groove. Fluid so supplied to the wall of the valve sleeve H' travels upwardly and downwardly from the groove 60 in the small working clearance space (e. g. .002") between the plunger H and sleeve H'. The downwardly traveling fluid is used for lubrication somewhat the same as in said Patent No. 2,219,229 through the intermediary of a reservoir groove 61 and flows through ducts 62 in the wall of the valve sleeve H' to a lower bearing portion of the ball head. The fluid which travels upwardly along the outer surface of the valve plunger H is intercepted by reservoir groove 64 and returned to a center bore 65 leading downwardly from inside the working chamber of the servo-motor 50 into communication with the groove 64 through radial holes 66.

At the start of the operation of the governor the piston and cylinder chamber of the servo-motor 50 is practically empty, fluid having been squeezed out of the chamber as slip by the force of the speeder spring M. This allows the spring to become extended so that it has initially less force to oppose outward movement of the fly balls than it has during normal operation. Thus with the speeder spring M, in effect, relieved or slackened off at the start the fly balls L quickly attain their normal operating position and begin to check the speed of the engine before it has attained full speed. But since raising of the pilot valve plunger H places the groove 56 in communication with constant pressure fluid in the hydraulic system, as evident from Fig. 1, the special servo-motor 50 becomes rapidly filled with operating fluid and the effective force of the speeder spring M is then increased to normal for the particular set speed.

The working clearance of the valve plunger and sleeve between the grooves 60 and 64 of the plunger H can be such as to regulate the supply of fluid to the servo-motor 50 so that the servo-motor becomes filled just as the engine attains normal running speed; or suitable means for adjustably metering fluid to the servo-motor can be used (e. g. a needle valve, not shown).

To limit the capacity of the working chamber of the servo-motor 50 so that the speeder spring is always compressed the same amount by the servo-motor, leak-off vents may be provided in the wall of the servo-motor cylinder, as at 68. Alternatively, coacting shoulders (not shown) can be formed on the piston and cylinder definitely to limit upward movement of the lower speeder spring retainer 52 relative to the pilot valve plunger H.

During normal operation the piston and cylinder surfaces of the servo-motor 50 turn relative to each other so as not to prevent rotation of the pilot valve plunger H through engagement of the ball arms L with the thrust member h. At the start it does not matter particularly whether or not the pilot valve plunger turns in its valve sleeve H' and it might not turn if the 75

piston 54 is bottomed in the cylinder 51 at the start of the governing operation.

The cushion start servo-motor 58 may be eliminated (antifriction bearing assembly used in its location as in my said Patent 2,219,229) and a modified form of power head valve such as shown at 10 in Fig. 3 used instead of the power head valve 21 of Figs. 1 and 2. The valve 10 cooperates with the remainder of the power head 10 to perform the same function as the valve 21 as well as to perform the function of the servo-motor 58 in preventing overshooting in speed upon starting the prime mover from rest to an adjusted speed.

The power head valve 10 has a cylindrical stem 11 which fits slidably but snugly within the axial bore 17 in the piston stem 11, there being no free exit paths for fluid therebetween as provided between the stem 21 and the bore 17 in Fig. 1. Instead, a central bore 72 in the stem 11 extends from the neck portion 32 (the bore 72 having divergent branches at this point) upwardly to near the top of the stem 11 where it intersects a through diametral bore 15. Together with the bore 31 the bores 72 and 15 provide an exit for fluid from the chamber beneath the piston 12. The fluid exit thus provided is adjustably restricted at the intersection of the bores 72 and 15 by a needle valve 16 threaded axially into the top of the stem 11 and held in adjusted position as by a compressible (e. g. fiber) lock washer 18.

In the operation of the modification of Fig. 3, (assuming the cylinder 14 remains charged with operating fluid; since the fluid cannot leave the cylinder), when the bell crank lever 36 of the speed adjusting mechanism moves the power head valve 10 downwardly, the restricted outlet at the needle valve 16 does not permit the piston 12 to move as fast as the valve 10 is moved. The piston 12 and the stem 11 move at a speed predetermined by the adjusted position of the valve 16 regardless of the rate of movement of the bell crank 36 and thus the left end of the speeder lever U is moved downwardly at a controlled rate to effect a gradual compression of the speeder spring M. As a result the spring M exerts a gradually increasing restraining force on the outward movement of the fly balls L and thus the prime mover accelerates at a controlled rate to the adjusted speed position with no tendency to overshoot. The time delay action provided by the needle valve 16 is not effective upon upward movement of the valve 10 and therefore the power head of Fig. 3 operates as in Fig. 1 when the bell crank lever 36 is moved to slow down the prime mover.

I claim:

1. In a speed governor the combination with speed setting means, centrifugally acting means operatively adjusted by the speed setting means, and speed regulating means controlled by the conjoint action of the aforesaid two means; of hydraulically acting means operatively interposed between the speed setting means and centrifugally acting means and operable automatically at commencement of governor operation in a manner to delay the application of the force of the speed setting means at its adjusted value on the centrifugally acting means.

2. In a speed governor the combination with speed setting means including a speeder spring, centrifugally acting means operatively adjusted by the speed setting means, and speed regulating means controlled by the conjoint action of the

aforesaid two means; of hydraulically acting means operatively connected with the speeder spring and operable automatically at commencement of governor operation in a manner to delay the application of the force of the speeder spring at its set value on the centrifugally acting means.

3. In a governor the combination with a speeder spring, governing means controlled in part thereby, and adjusting means for adjusting the effective force of the spring to change speed setting; of means constituting a fluid pressure operative device operatively interposed between said adjusting means and said spring and operative to cause the speeder spring to assume a stress corresponding to a given increased speed setting of the adjusting means a substantial time after movement of the adjusting means to an increased speed position.

4. In a speed governor, speed weighing means including a speeder spring and a valve member controlled in part thereby in accordance with effective force exerted by the spring to cause a speed regulating operation, a speed adjusting element operatively connected to the spring, a hydraulically acting means interposed between the speed adjusting element and said valve member and arranged to cause a gradual increase in the effective force of the spring on said valve member independently of the adjusted position of said adjusting element.

5. In a hydraulic relay speed governor, speed weighing means including a speeder spring and a pilot valve member controlled in part thereby in accordance with effective force exerted by the spring to cause a speed regulating operation, a speed adjusting element operatively connected to the spring, a hydraulically acting means interposed between the speeder spring and said pilot valve member in a manner gradually to increase the effective force of the spring on said pilot valve member independently of the speed of adjustment of said adjusting element, and means operative to supply a limited volume of hydraulic fluid to the hydraulically acting means during commencement of operation of the governor.

6. In a hydraulic relay speed governor the combination with a speed adjusting means, a speeder spring operatively associated with said speed adjusting means and a centrifugally actuated controlling element of the governor, of means constituting a fluid pressure operated time delay device interposed between the speed adjusting means and the speeder spring and acting to effect delay only in the speed increasing direction.

7. In a speed governor, speed weighing means including a speeder spring and a member controlled in part thereby in accordance with the effective force exerted by the spring to cause a speed regulating operation, a speed adjusting element, and a hydraulic motion transmitting means interposed between said adjusting element and said spring, said last named means comprising a valve member arranged to be moved by said speed adjusting element, a follow-up piston associated with said valve and controlled thereby to vary the effective force exerted by the spring, and a restricted fluid venting means associated with the valve member in a manner to cause the follow-up motion of the piston to be slower in the direction to increase speed than to decrease speed.

8. In a speed governor, speed weighing means including a speeder spring and a member controlled in part thereby in accordance with the

effective force exerted by the spring to cause a speed regulating operation, a speed adjusting element operatively connected to the spring, and a hydraulic motion transmitting means interposed between said adjusting element and said spring, said last named means comprising a valve member movable by said speed adjusting element, a piston associated with said valve and controlled thereby to change the effective force exerted by the spring, and adjustable means to retard the rate of movement of said piston in one direction only with respect to the rate of movement of said

9. In a hydraulic relay speed governor mechanism, means arranged to commence to build up a supply of operating fluid pressure in the governor mechanism as soon as said mechanism begins to operate, a pilot valve and speed regulating servomotor controlled by the pilot valve, speed responsive means controlling the pilot valve, a speeder spring for variably opposing a speed responsive element of the speed responsive means, an adjustable speed setting means for varying the opposing force of the spring, and hydraulically acting means supplied with fluid by said first named means and operatively interposed between the speed setting means and the pilot valve in a manner to act on the speeder spring, independently of adjustment of the speed setting means, to cause the speeder spring to exert an increasing force opposing said speed responsive element as the operating pressure is built up by the first named means.

10. In a hydraulic relay speed governor mechanism, means for supplying the governor with hydraulic pressure, said means being arranged to commence to build up a desired operating pressure as soon as the governor mechanism begins to operate, a speed regulating servomotor and a pilot valve including a shiftable valve element operable from a neutral position in opposite directions to control the servomotor, a speed responsive means connected to the shiftable valve element, a speeder spring associated with the speed responsive means in a manner to oppose operation thereof in one direction, an adjustable speed setting means for varying the opposing force of the spring, hydraulically acting servomotor means supplied with hydraulic fluid through said shiftable valve element and interposed between said latter element and the speeder spring so as to cause relative movement therebetween, said hydraulically acting servomotor means being arranged to cause the speeder spring gradually to exert an increasing force opposing said speed responsive element as the operating pressure is built up by the first named means.
